UNITED STATES PATENT OFFICE.

EDWARD J. ROBERTS, OF ASHLAND, KENTUCKY, ASSIGNOR OF ONE-FOURTH
TO WM. W. CULBERTSON, OF SAME PLACE.

CAR-BRAKE.

SPECIFICATION forming part of Letters Patent No. 316,829, dated April 28, 1885.

Application filed April 30, 1884. (No model.)

To all whom it may concern:

Be it known that I, EDWARD J. ROBERTS, a citizen of the United States, residing at Ashland, in the county of Boyd and State of Kentucky, have invented certain new and useful 5 Improvements in Automatic Car-Brakes, of which the following is a specification.

My invention relates to that class of car-brakes in which the momentum of each car of 10 the train is employed to effect the application of its own brakes whenever a crowding of the cars occurs, caused by a more or less complete stoppage of the engine or forward cars.

In order that my invention may be fully understood, I will proceed to describe it with 15 reference to the accompanying drawings, in which—

Figure I is a plan view of the draft-timbers of one end of a freight-car with my invention 20 applied. Fig. II is a detail elevation of the locking mechanism therein employed. Fig. III is a perspective view of one end of a box or freight car, showing mechanism for operating the locking mechanism from the roof 25 thereof. Fig. IV is a view similar to Fig. I, showing a modified form of the braking and locking mechanism. Fig. V is a side elevation of the same, and Fig. VI is a perspective view of the automatic operating-lever detached.

The draw-bar 1 and coupling 2 employed in 30 my improved brake system may be of any ordinary or approved construction. It is preferred, however, to use substantially that form which I have made the subject of an application 35 for patent of even date herewith, in which the link-retaining hook 3 is placed within the draw-bar head and transmits strain not to said draw-bar head, but to the draft or follower plates 4, and thence through the draw-spring 5 to the timbers of the car-frame. In 40 this case the draw-bar head serves merely the purpose of a buffer, acting through the draw-spring 5 and the rear plate, 4. A second spring, 5^a, is placed on the draw-bar within 45 the draw-head 1, and keeps the said draw-bar normally in its forward position by bearing against the rear side of the flange or collar secured thereto. It will thus be observed that the draw-bar and draw-head move entirely in- 50 dependent of each other, each transmitting its

movement to the car-frame through the medium of the spring 5 and plates 4.

Pivoted to the car-frame at 6 is my improved automatic brake-lever, 7, the shorter end of which is turned up, as shown at 8, Fig. V, to 55 be engaged by the forward follower-plate, 4. The longer arm of the lever 7 is extended beyond the draft-timbers and slotted longitudinally at 9, to receive the customary hand-brake connecting-rod, 10. The connecting-rod 10 60 has loose bearing at 11 in a bracket fixed to the car-timbers, and is connected at its forward end by means of chain 12 to the customary hand-brake shaft, while at its rear end it has connection with the brake-lever chain. A spiral 65 spring, 13, interposed between the bracket 11 and the end of the rod 10 serves to retract said rod and release the brakes after application. A second spiral spring, 14, is placed upon the rod 10 between the end of the lever 7 and a 70 stop-arm, 15, which latter is pivoted to the timbers of the car at or near one end, and is also provided with a loose connection with the rod 10, such as will permit a relative movement between them in a horizontal plane. 75 The connection between the rod 10 and arm 15 may be a slotted one, as represented in Fig. 4, if desired; but this is not deemed necessary, for the reason that the arc through which that portion of said arm moves is so 80 short that the greatest distance from the chord to the periphery is so slight as to be readily compensated for by the deflection of the rod itself, which is permitted by the slot in the end of the lever 7. It is only necessary, 85 therefore, that the connection be such that they may move freely in a horizontal plane without binding.

In the preferred form of the device, or that shown in Fig. I of the drawings, the stop or 90 locking arm 15 is extended to the side of the car, where it travels in a guide, 23, and has a projecting handle, 24. Here, also, a spring, 25, is inserted between the arm 15 and nut 16 on 95 brake-rod 10, for easing the effect on said rod of the sudden stopping of the arm 15. By screwing up the nut 16, the relative positions of the parts 7 15 and tensions of springs 13 14 25 may be adjusted as desired.

In operation a crowding of the cars of the 100

train, resulting from more or less complete stoppage of the engine or one of the forward cars of the train, will act to press the draw-bar head or buffer 1 in against the plate 4, comprising spring 5, and carrying said plate 4 and the inner end of lever 7 inward, thus compressing the springs 14 25 against the nut 16, thereby extending said rod and applying the brakes. It will be seen that the brakes will be set with a force proportional to the strength of springs 14 25, and by the yielding pressure thus obtained all sudden shocks on the brake mechanism are avoided.

When yarding, switching, and backing heavy freight-trains, a contingency may arise when it will be desirable to have the automatic brake mechanism capable of being prevented from action while the hand-brakes remain effective. To this end I employ a locking device or device, consisting of a bar, 17, which may be a spring-bar, or may be pivoted at one end to the car-timbers, having a lug or stop, 18, projecting downwardly therefrom in such position as, when lowered, to engage with either side of arm 15, as shown in Fig. I, and by arresting it at either extremity of its movement prevent the spring 14, when compressed by the lever 7, from extending the brake-rod 10, or, if the brakes are applied, prevent the return of the lever 15 for releasing them, as the case may be. The bar 17, if of spring metal, will be arranged, when in normal position, to be disengaged from arm 15 and be forced down into engagement by a cam or other projection, 35 19, on the inner end of a shaft, 20, adapted to be operated from the side or roof of the car, as may be desired.

In Fig. III is shown a mode of operating the cam-shaft 20 from the top of a box-car, one end 40 of the said shaft being provided with rock-lever 26, to the ends of which the cable or chain 21 is attached. The other ends of said cable are fixed to a pulley or lever, 27, under the control of hand-wheel 28 at the top of the car. 45 A crank or cranks, 29, being provided on the ends of shaft 20 at one or both sides of the car, it will be seen that the automatic locking mechanism may be operated from the ground as well as from the roof of the car; or the normal position of the bar may be with its lug 18 50 in engagement with the arm 15, it being raised from engagement, when desired, by means of a chain or rod, 21, leading from the end thereof to a lever, 22, above the car-roof.

55 It will be observed that when the arm 15 is in its normal position and the lug 18 in engagement therewith the action of the automatic mechanism will be arrested, while the hand-brake mechanism may be operated as before. The brakes may thus be locked on after removal of strain on the draw-bar; or the automatic mechanism may be locked out of position, while the hand-brake is allowed free operation; or by raising the stop 18 out of contact with the arm 15 free play of the automatic braking mechanism is permitted. The

free action of the brake-lever and draw-head is never interfered with, whether the brake be locked on or off.

I am aware that car-brakes adapted to be applied by the crowding of the cars have been provided with means for locking the brakes on and unlocking them automatically, but do not see the utility of such a device. With it the brakes are applied and locked by each inward thrust of the draw-bar, and released as soon as said draw-bar is drawn out. This is the equivalent of having no locking device at all, so far as the purpose of my invention is concerned, as with it the brake cannot be locked when the train is in motion, which is often necessary in the case of the rear car of a train.

I am also aware that buffers located on one side of the draw-bar have been employed for actuating automatic brakes of the class in question; but these are objectionable, for the reason that they are not at all times equally effective. For example, in turning a sharp curve, if the buffer be on the side of the draw-bar next the outer edge of said curve, they will not operate, or at least not as effectively as if it were on the inside; and I am also aware that such brakes have been provided with means for preventing their automatic application only, and do not claim such devices as my invention.

Having thus described my invention, the following is what I claim as new therein and desire to secure by Letters Patent: 100

1. The combination, with a draw-bar and a draw-head or buffer surrounding the same and moving independently thereof, of a pivoted lever engaging with the brake-rod at one end, and adapted to be engaged and operated by the moving draw-head at the other, substantially in the manner and for the purpose set forth.

2. The combination, with the movable draw-bar or buffer, a brake-rod, and a lever for transmitting motion from the former to the latter, of a detent and hand-connections for operating said detent, whereby the brakes are locked on, as and for the purpose set forth.

3. The combination, with a movable draw-bar or buffer, a brake-rod, and a lever for transmitting motion from the former to the latter, of a locking-arm connected with and carried by said brake-rod, a detent for engaging therewith at either extremity of its permitted movement, and hand-connections for operating said detent for preventing the automatic application of the brakes or locking them while applied, substantially in the manner and for the purpose set forth. 115

4. The combination of the pivoted brake-lever 7, the brake-rod 10, the spring 14, the lever 15, the spring 25, and the nut 16 on the brake-rod, all constructed and arranged substantially as and for the purposes set forth. 125

5. The combination of brake-lever 7, brake-rod 10, lock-arm 15, nut 16, and a detent for

controlling the movement of the lock-arm, as explained.

6. The combination of the brake-lever 7, brake-rod 10, and lock-arm 15 with the spring-arm 17, having lug 18, and the shaft 20, having cam 19, as and for the purposes set forth.

7. The combination of buffer or draw-bar head 1, brake-lever 7, brake-rod 10, spring 14, lock-arm 15, and stop 18, as and for the purposes set forth.

8. In combination with locking-arm 15 and stop 18, the cam-shaft 20, having crank 29, for the purposes set forth.

9. In combination with stop-operating shaft 20, the hand-wheel 28 and the cable 21, connecting said shaft and wheel, whereby the former is operated by the latter, as explained.

10. In combination with the stop-operating shaft 20, the rock-lever 26, cable or chain 21, pulley or lever 27, and hand-wheel 28, all connected and adapted to operate substantially as set forth.
